UNITED STATES PATENT OFFICE.

WALTER E. JENSEN, OF LOS ANGELES, CALIFORNIA.

DESIGN FOR A COMBINATION MOTOR CASING AND SUPPORTING STAND.

60,865.

Specification for Design.

Patented Apr. 18, 1922.

Application filed July 13, 1921. Serial No. 484,501. Term of patent 3½ years.

To all whom it may concern:

Be it known that I, WALTER E. JENSEN, a citizen of the United States, residing at Los Angeles, in the county of Los Angeles and State of California, have invented a new, original, and ornamental Design for a Combination Motor Casing and Supporting Stand, of which the following is a specification, reference being had to the accompanying drawing, forming part thereof.

The figure is a perspective view of a combination motor casing and supporting stand embodying my design.

I claim:

The ornamental design for a combination motor casing and supporting stand, as shown.

WALTER E. JENSEN.
